UNITED STATES PATENT OFFICE.

FRED P. WAHLGREN, OF TACOMA, WASHINGTON.

BOOK.

Application filed September 15, 1924. Serial No. 737,835.

The invention relates to books and especially to that class of book whose sheets are removably bound therein.

The objects of the invention are to produce, first, a bookbinding or container which will protect the book leaves when it is permanently mounted in the open air, as on a lamp-post, for the purpose of giving information as to the city and the firms listed therein; second, which, when so mounted, will cause the leaves of the book to separate and move out of the fixed part of the container as the cover portion thereof is opened; third, in which the sheets are mounted in groups, any of which may be removed from the container, the sheets composing the group thus removed may then be redistributed, removed, or replaced, at will and the group rebound in the book; fourth, in which the sheets are so mounted in the container that the pages will lie fully open and substantially flat, irrespective of whether they are in one portion or another of the book; fifth, in which all the sheets are cut in identical manner and can therefore be used in any portion of the book; sixth, in which the sheets are fastened in the book by means of removable metal binding which is locked in the container and which may be used over and over again; seventh, in which the book cover is hinged to the back, and the hinge pintle thereof supports a plurality of intermediate or secondary hinge links, to each of which two groups of sheets are pivotally attached, whereby the book will open just as readily and completely at one portion as at another; eighth, in which such secondary hinge links are formed so that when one is reversed its primary hinge barrels will fit between those of the other hinge link and yet so that in either case the secondary hinge portions thereof are in exactly corresponding positions, so that the sheets secured to the one hinge link will be in the same vertical alignment as those secured to the other hinge link; ninth, in which the back, top and cover of the container, the secondary hinge links, the locking bars, and the metal sheet binding may all be stamped and pressed out of metal, thereby keeping the cost of such containers down to a low point; tenth, in which the cover of the container is secured to the pintle of the primary hinge and said pintle is spring actuated to keep the cover closed; and eleventh, to provide a removable sheet book which is neat in appearance, cheap to

make, easy to manufacture in large quantities, and which may be used for a great variety of purposes.

I attain these and other objects by the devices, mechanisms, and arrangements illustrated in the accompanying drawings, in which:

Fig. 1 is a section of a book formed in accordance with my invention, looking towards the top edge;

Fig. 2 is a rear elevation of the book, on a smaller scale;

Figs. 3 and 4 are perspective views of the two secondary hinge links;

Fig. 5 is a side elevation of the wire sheet binding;

Fig. 6 is an elevation of the central portion of a sheet forming part of the book, showing the binding slots and folding crease therein;

Fig. 7 is a perspective view of the locking bar;

Figs. 8 and 9 are perspective views, on an enlarged scale, showing a portion of the secondary hinge link, the locking means, and the sheet binding means, assembled without any sheets, in locked and in unlocked positions, respectively;

Fig. 10 is a vertical section of the pintle spring and its housing; and

Fig. 11 is a section of the pintle and a portion of the book cover, showing the means for securing the cover to the pintle, whereby it is turned into closed position under the action of the pintle spring.

Figs. 3 to 7, inclusive, are all made to the same scale and are placed so that each part is in corresponding horizontal line in the said several views.

Similar numerals of reference refer to similar parts throughout the several views.

The primary use to which this book is designed to be put is for a street directory where it will be supported in vertical position on lamp-posts, walls, or other supports, especially at street corners, and will contain information about the city, maps of contiguous territory, together with a classified directory of firms; but it is, of course, to be understood that it may be used for many different purposes, in fact, for any purpose to which any book may be put.

The book, therefore, comprises a metal container, with a front cover hinged thereto, and groups of leaves secured therein. The container is intended to protect the

leaves from the inclemency of the weather and from wear. In order to enable the book to be kept up to date in its information, without having to reprint a large portion of it at each correction, it is constructed on the looseleaf order in which each group of sheets may be removed from the binding and any sheet of the group removed and, if desired, one or more new sheets substituted and then the entire group reinserted in the book, and such removal and substitution will be easily and quickly performed without having to remove the container from its permanent support. In order to enable the book to be easily opened at a desired page, using one hand only since the other hand is often engaged in carrying articles, when used as a street directory, I have arranged the parts in such manner that the leaves are drawn out of the container as the cover is opened, whereby the hand which holds back the cover, against its closing spring, can readily pick out the page at which it is desired to look, and so that any such page will lie flat and open and thus can readily be read. Also all four pages of each sheet may be used.

Referring now to the drawings, the container comprises a box formed of pressed aluminum, or other suitable material, having a back plate 1, by means of which it may be fastened in vertical or inclined position to the support (not shown), if desired; an edge plate 2; and a top plate 3. The top plate 3 may extend over the container to a greater depth than the edge plate 2 and also may extend to a greater width than the container, thus forming an effective roof for the book contents. The top plate 3 may also be bent up into a front plate 4, on which suitable lettering may be placed for the purpose of identification or for indicating the street intersection at which the book is placed, if desired.

A cover plate 5, also preferably formed of pressed aluminum, is provided and is adapted to close the front of the container. In general, I prefer to omit any closure of the bottom edge of the container, thereby facilitating reaching and turning the leaves of the book when in use, but it is to be understood that such a bottom may also be provided, formed integral with the back plate 1, bent forward, or with the cover plate 5, bent backward. The cover plate 5 may also have suitable lettering on its surface, as above mentioned for the front plate 4.

The back plate 1 is bent forward along its left edge, at an angle, as shown, to form the inclined portion 6, and the edge of this portion 6 is cut and rolled to provide a plurality of hinge barrels 7, four are shown in the drawings. The cover plate 5 is complementarily bent rearward along its left edge to form the inclined portion 8, and the edge of this portion 8 is cut and rolled to provide

a plurality of hinge barrels 9. The hinge barrels 9 of the cover are located above the corresponding barrels 7 of the container, therefore when the container is mounted in vertical position the cover is supported by the barrels 7 and not by the pintle of the hinge. The said barrels 7 and 9 are positioned in pairs, four pairs being shown in Fig. 2, and the upper and lower pairs are separated from the center two pairs by spaces which are filled by the barrels of the hereinafter described secondary hinge links. A single pintle 10 passes through all the barrels 7 and 9 as well as through those of the said secondary hinge links, and also passes upward through the top plate 3. A small slot 11 is made in the pintle 10 (Fig. 11) about half way down the side of the book, and a thin plate 12 is secured to the part 8 of the cover 5 and enters the said slot 11, thus attaching the cover plate to the pintle in such manner that the pintle will turn with the cover as it is opened or closed. A spring 13, preferably a flat coiled spring, is secured to the top of the pintle 10, by having its inner end enter a slot 14 in the upper end of said pintle, and is enclosed in a box or cap 15, which is held from rotating by means of lugs 16 which pass through suitable slots 17 in the top plate 3 of the container, said spring 13 being secured at its outer end to said box 15 by being bent through a slot therein. Thus the tension of the spring 13 can easily be regulated by raising the cap 15 sufficiently to draw the lugs 16 out of the slots, turning the cap, and reinserting the lugs in position. Thus it will be seen that the above described parts form a container which is made of only two pieces of metal stamped and pressed to shape and adapted to hold and to protect the sheets and adapted to be used in vertical or in any other position, as desired.

The secondary hinge links 18 and 19 (Figs. 3 and 4) are also made of stamped and pressed aluminum, or other suitable material, and are identical. However, the hinge link 19 is assembled in the book in reversed position from the hinge link 18. Each hinge link consists of a plate suitably cut out and bent to form the series of primary barrels 20 and 21, respectively, through which the above-described pintle 10 passes when the book is assembled. These barrels are all joined by the vertical plates 22 which thus cause all the parts to turn together on the pintle 10. A double series of hooks 23 and 24 extend from the plates 22, the hooks 23 turning back in one direction while the hooks 24 turn in the opposite direction. The hooks 23 and 24 are arranged side by side. In the drawings six sets of such hooks 23 and 24 are shown, for each of the hinge links 18 and 19.

A lock bar is also made of stamped and

pressed aluminum and is shown in Fig. 7. This consists of a plate bent into U-shape so as to have two legs 25 and a central web 26. It is slightly longer than either of the two hinge links 18 or 19. The central web 26 is cut at various points positioned to come opposite to the hooks 23 and 24, above described, and said cuts are extended downward and widened into the legs 25, as clearly shown in Figs. 7, 8 and 9. When the lock bar is assembled on the hinge link the two legs 25 lie on each side of the main plates 22 and, when in its normal or locking position (Fig. 8), the edges of the cut portion 10 close the opening of the hooks 23 and 24 while, when it is in its raised position (Fig. 9), the broader part of the cut comes in line with the hooks and thus a space is made opposite the openings of these hooks of sufficient size to permit the entry or withdrawal 20 of the binder wire into or out of said hooks.

The sheets 27, of which the book is formed, are provided with a series of cuts or slots 28 on their center line, and are folded on 25 this line, (Fig. 6). These slots 28 are positioned and spaced to come opposite to the hooks 23 and 24, of the hinge links above described, and they are equally spaced and symmetrically placed relatively to the top 30 and bottom edges of the sheets 27, so that each sheet is exactly like every other sheet and can be printed with either edge uppermost. The sheets are folded one within the other to form a group, and all the slots in 35 the group align to permit the binder wire offsets to pass therethrough.

The binder wire 29 (Fig. 5) is made of stiff wire or cut from sheet metal, and is provided with offsets 30, each positioned in 40 line with the slots 28 of the sheets 27 and adapted to pass therethrough into the hooks 23 or 24. The said offset portions 30 thus form the secondary pintles of the binding and as they pass through all the slots in the 45 sheets and lie inside the inner fold of the group of sheets they bind the sheets to the hinge links, and the hinge links bind them to the container, and the lock bar closes the hook openings and prevents the accidental removal of the group of sheets. As above, 50 the binder offsets extend through the sheets and said extending portion forms, with the sheets, a closed rectangular ring, one side of which engages the corresponding hook of the hinge link, and is free to turn therein as a hinge pintle.

In opening the book, the cover plate 5 swings on the container and turns the pintle 10 with it. The barrels 20 and 21 of the hinge links tend to turn with the pintle 10 on which they are mounted and thus, as the cover plate is opened, the leaves tend to come out of the container and this effect is aided by the fact that all the barrels 20 and 60 21 of the hinge links lie above and are sup-

ported by the barrels 9 of the cover and therefore tend to turn with their support, thus the book is automatically opened out, the leaves separating, as the cover of the book is opened, thus greatly facilitating the 70 finding of the page on which the desired information is recorded.

The book therefore consists of a metal binding or container, having the front cover hinged to the rear to open out flat; two secondary hinge links supported on the same hinge as the front cover, and dividing the sheets in the book into two distinct and independent groups; and four groups of leaves, each independently bound to one of the 75 hinge links and free to turn thereon as on a secondary hinge, two of the groups being supported on one hinge link and two on the other; together with a locking bar on each hinge link to prevent the accidental removal 80 of either of the groups of sheets mounted thereon.

Having therefore described my invention, what I claim, is:—

1. A book comprising a supported metal 90 pintle; a metal hinge link mounted on said pintle and provided with a series of hooks; a group of sheets, folded one within the other and slotted along portions of the fold; and a metal binder lying within the fold 95 of the innermost sheet of said group and bent with offsets, each offset extending through the corresponding slot of said group of sheets and projecting therefrom into engagement with the corresponding hook on 100 said metal link.

2. A book as set forth in claim 1, wherein the hinge link is provided with a double series of hooks, lying side by side, the hooks of one series each adapted to receive the corresponding projecting offset portion of the metal binder of one group of sheets, and the hooks of the other series correspondingly functioning with the metal binder of another 105 group of sheets.

3. A book as set forth in claim 1, wherein the hinge link comprises a plate extending parallel with the pintle, a plurality of hinge barrels extending from one edge thereof and encircling said pintle, and a plurality of hooks extending from the other edge, each adapted to receive the corresponding projecting offset portion of the metal binder. 115

4. A book as set forth in claim 1, wherein a plurality of said metal hinge links are provided, each similar the one to the other, but one hinge links mounted in reversed position from the other, each comprising a plate extending parallel with the pintle, a plurality of hinge barrels extending from one edge 120 thereof and encircling said pintle, the barrels of one hinge link fitting above the barrels of the reversed hinge link, and each provided with a plurality of hooks extending from the other edge, each hook adapted 125 130

to receive the corresponding projecting offset portion of the metal binder, the hooks of the several hinge links being similarly positioned, each to each, relatively to the upper and lower edges of the book.

5. A book comprising a supported metal pindle; a hinge link mounted thereon and provided with hooks; a group of sheets, folded one within the other and slotted along portions of the fold; a metal binder lying within the fold of the innermost sheet of the group and bent with offsets, each offset extending through the corresponding slot of said group of sheets and projecting therefrom and engaged by the corresponding hook; and removable means for blocking the openings of said hooks, whereby said binder and groups of sheets are locked in position.

6. A book as set forth in claim 5, wherein 20 said locking means comprises a bar slidably mounted on said hinge link and slotted to permit the hooks to pass therethrough, the edge of the slots blocking the openings of the hooks.

25 7. A book as set forth in claim 5, wherein said locking means comprises a bar slidably mounted on said hinge link and slotted to permit the hooks to pass therethrough, the slots thereof extending downward and 30 widening below the normal relative position of the hooks, whereby when the bar is in its normal position the edges of said slots block

the openings of the hooks but when it is in raised position the edges of the widened portions are removed from the hooks to permit 35 entry thereto.

8. A book comprising a container; a pindle mounted on the container to form a hinge; a cover mounted on said pindle; a group of sheets within the container; and 40 means for securing said group of sheets to the pindle.

9. A book as set forth in claim 8, wherein the cover is attached to the pindle and the pindle is rotatably mounted on the container, whereby the pindle turns with the cover as it is opened or closed, and whereby the group of leaves is moved out of or into the container as said pindle turns.

10. A book comprising a container; a pindle rotatably mounted on the container to form a hinge; a cover attached to said pindle and rotating therewith to close the container; a hollow cap into which the end of said pindle projects and adjustably attached to said container; and a spring coiled around said pindle and connected at its ends to said pindle and to said hollow cap, whereby the force applied by the spring to the pindle will move the cover to close the container, and 55 whereby the said force may be adjusted by adjusting the cap on the container.

FRED P. WAHLGREN.
